SHOWER CURTAIN CLAMP

Saul Gubernick, San Jose, Calif.

Application June 10, 1953, Serial No. 360,633

1 Claim. (Cl. 248—206)

This invention relates to a shower curtain clamp.

An object of this invention is to provide a clamp by means of which one or both vertical edges of a shower curtain may be clamped relative to adjacent walls or the tub so as to hold the curtain against blowing inwardly.

Another object of this invention is to provide a shower curtain clamp of this kind which can be detachably connected with the curtain and with the adjacent walls or a portion of the tub.

A further object of this invention is to provide a clamp of this kind which will hold the curtain against blowing inwardly and at the same time will permit slight movement of the curtain so that the latter will not be torn by pressure applied from either side of the curtain.

These and ancillary objects and structural features of merit are attained by this invention, the preferred embodiment of which is set forth in the following description and illustrated in the accompanying drawing.

In the drawing:

Figure 1 is a detailed side elevation of a shower curtain clamp constructed according to an embodiment of this invention showing the clamp in applied position with the curtain and support in fragmentary side elevation.

Figure 2 is a sectional view taken on the line 2—2 of Figure 1.

Figure 3 is a sectional view taken on the line 3—3 of Figure 2.

Figure 4 is a sectional view taken on the line 4—4 of Figure 2.

Referring to the drawing, the numeral 10 designates generally a shower curtain and the numeral 11 designates generally a vertical wall disposed adjacent one edge of curtain 10. The lower portion of the curtain 10 projects downwardly into tub 13. In order to provide a means whereby the curtain 10 will be held against inward sway relative to the tub 13, I have provided a clamping means for connecting the adjacent edge 12 of the curtain 10 with the supporting or vertical wall 11. This clamp is formed of a pair of parallel jaws 14 and 15 which are formed at their outer ends with eyes 16 and 17.

A pair of rubber jaw members 18 and 19 having reduced stems 20 and 21 are adapted to engage on opposite

2

sides of the curtain 10. The eyes 16 and 17 engage in the reduced stems 20 and 21 of the clamping members 18 and 19 respectively.

The outer ends of the arms or resilient members 14 and 15 merge with crossed bars 22 and 23 extending from the arms 14 and 15 respectively and the bars 22 and 23 merge with parallel bars 24 and 25 respectively. The ends of the bars 24 and 25 merge with convergent bars 26 and 27 respectively and the bars 26 and 27 are formed integral with 10 an eye or ring 28.

A double looped link 29 having an eye or ring 30 engaging the eye 28, is loosely connected with a reduced diametric shank 31 which is carried by a stem 32. The stem 32 extends from a suction cup 33 and the latter is adapted to be pressed against the adjacent vertical side of the wall 11. The double looped link 29 includes a small eye or ring 34 which engages about the reduced diametric shank 31.

In use and operation of this clamp, the rubber jaw members 18 and 19 may be initially clamped on opposite sides of the curtain 10 adjacent one vertical edge thereof by pressing the arms 24 and 25 inward. Releasing of the arms 24 and 25 will permit the resilient arms 14 and 15 to move toward each other and thereby resiliently hold the jaw members 18 and 19 against the shower curtain 10. The suction cup 33 may be engaged with the adjacent face of the wall 11 or if this wall 11 is relatively porous the suction cup 33 may be engaged with a selected portion such as the rim of the tub 13.

30 The clamp hereinabove described is preferably used in pairs with one clamp at each vertical edge of the shower curtain and when in applied position will releasably hold the lower portion of the shower curtain against inward swinging.

35 What is claimed is:

A shower curtain clamp comprising a pair of parallel wire bars, circular eyes formed integrally with the terminal ends of said bars, a pair of cylindrical rubber jaws having aligned, confronting inner ends, each of said jaws having an annular groove formed therein with one of said eyes being positioned in each of said grooves, a second pair of parallel wire bars, crossed connecting members connecting one member of each pair of bars with an opposite member of the other pair of bars, inwardly converging bars extending from the inner ends of said second pair of parallel wire bars, an integral spring eye connecting the inner ends of said converging bars, a suction cup, and a link connecting said suction cup with said eye.
